UNITED STATES PATENT OFFICE.

WILLIAM W. BURKE, OF BENNINGTON, VERMONT, ASSIGNOR OF ONE-FOURTH TO JAMES E. BURKE AND ONE-FOURTH TO ALEXANDER J. COOPER, BOTH OF BENNINGTON, VERMONT.

STOP-MOTION MECHANISM FOR KNITTING-MACHINES.

1,148,076.

Specification of Letters Patent. Patented July 27, 1915.

Application filed August 22, 1913. Serial No. 786,106.

To all whom it may concern:

Be it known that I, WILLIAM W. BURKE, a citizen of the United States, residing at Bennington, in the county of Bennington 5 and State of Vermont, have invented new and useful Improvements in Stop-Motion Mechanism for Knitting-Machines, of which the following is a specification.

This invention relates to an improved 10 stop motion for machines in which a thread or strand of yarn is employed either for knitting or weaving, the mechanism herein-after described and embodying my invention 15 being particularly adapted to knitting machines.

The object of the invention is to provide a stop motion for machines of the character set forth and especially for knitting machines in which when the normal feeding of 20 the yarn to the machine is interrupted the stop motion will be operated to stop the machine very quickly, but without jarring or injuring the same. The mechanism operates to stop the machine when the thread 25 or yarn breaks or when abnormal tension is brought to bear upon the thread or yarn and also when the thread runs out on the bobbin.

In the mechanism hereinafter described two devices are employed for making and 30 breaking the circuit. One of these devices embodies in its construction a drop device which is adapted to open and close an electric circuit, the device being so constructed and arranged that when a thread or yarn 35 breaks or when abnormal tension is brought to bear upon said thread or yarn the drop device will be operated to close the circuit. When the circuit is thus closed a tripper is 40 operated to release a spring-actuated member which is connected to a clutch mechanism and operates upon one member of the clutch mechanism to move the same and disengage the clutch from operative engagement with the main driving shaft of the 45 machine, and at the same time that the clutch is thus operated a friction brake is operated to stop the rotation of the shaft, the friction brake being operated for this purpose by the mechanism which disengages the 50 clutch from operative relation with the shaft.

It is desirable that when the clutch is thrown out and the main driving shaft stopped the electric circuit should be broken

and the second device for making and breaking the electric circuit is operated to produce this result, namely, to break the circuit, after the first device has performed its work of operating a tripper to release the spring-actuated member. 55

Preferably the first device referred to for closing the circuit upon the breaking of the strand of yarn or upon abnormal tension being brought to bear thereon is like that embodied in applicant's co-pending application Serial No. 766,685, filed May 10, 1913, 60 and the improvement thereon set forth in applicant's co-pending application Serial No. 784,923, filed August 15, 1913, to which applications, for specific details, reference 65 may be had. The other device for making and breaking the electric circuit may be of any suitable construction. 70

The invention consists in the combination and arrangement of parts set forth in the 75 following specification and particularly pointed out in the claims.

Referring to the drawings:

Figure 1 is a plan view of a stop motion mechanism embodying my invention. Fig. 2 is a front elevation of the same. Fig. 3 is a rear elevation of the same. Fig. 4 is an enlarged sectional elevation taken on line 4-4 of Fig. 2. Fig. 5 is a sectional elevation taken on line 5-5 of Fig. 2, illustrating 85 the friction clutch mechanism. Fig. 6 is a detail sectional elevation taken on line 6-6 of Fig. 5. Fig. 7 is a sectional plan taken on line 7-7 of Fig. 3. Fig. 8 is a sectional elevation taken on line 8-8 of Fig. 1. Fig. 9 is a perspective view of one of the circuit 90 making and breaking devices. Fig. 10 is a side elevation of the same. Fig. 11 is a transverse section taken on line 11-11 of Fig. 10. 95

Like numerals refer to like parts throughout the several views of the drawings.

In the drawings, 5 is the circuit closing device which is operated when the normal feeding of the yarn is interrupted either by 100 the breaking thereof or by abnormal tension thereon.

6 is a base in two parts, viz, a lower part 7 and an upper part 8, and these parts preferably are formed of insulating material 105 and in the upper part 8 a drop device 9 is slidably mounted, consisting of a wire bent in U-shape, the legs 10 constituting contact

points and the closed end of said drop device being bent at 11 to form a guide for a strand of yarn 12. When said strand of yarn breaks or the supply runs out, or when abnormal tension is applied thereto, the legs 10 will be caused, in a manner hereinafter described, to engage the contacts 13 which preferably consist of mercury inclosed in chambers 14 contained within the base 6. 10 The legs 10 are arranged to slide in holes 15 formed in the upper part 8 of the base, said holes leading into the chambers 14 from the top of said upper part 8. In the upper surface of the lower part 7 and immediately 15 above the chambers 14 washers 27 are provided which have holes 28 therein through which the legs 10 project into the chambers 14. These washers are preferably made of felt and prevent any of the mercury in the 20 chambers 14 from leaking out between the members 7 and 8.

When the electric circuit is open the parts will be in the position illustrated in Fig. 11. When the circuit is closed by the drop wire 9 the electromagnet 16 will be energized and the armature 17 of said electromagnet will be drawn toward said electromagnet and rock a vertical shaft 18 to disengage a tripper arm 19 fast thereto from an arm 20 pivotally connected to a rotary member 21.

The rotary member 21 is mounted upon a stud 22 fast to a bracket 23 which, in turn, is fastened to a cross-head 24 forming a portion of the frame of the machine, said frame 25 consisting, in part, of two side frames 25 and 26. The arms 20 are supplied in duplicate, as are also the tripper arms 19, and said arms have springs 29 connected thereto and operating, when released by the tripper arms 40 19, to move the spring-actuated member 21 in the direction of the arrow *a* (Fig. 1).

The main driving shaft 30 is journaled in suitable bearings 31 and 32 fast to the frame of the machine and to said shaft is 45 fastened a bevel gear 33 which meshes into another bevel gear 34, the latter gear being fastened to a vertical shaft 35 to which is fastened a spur gear 36 which meshes into a gear 37 fast to a running ring 38, and upon 50 said running ring the lower needle cylinder 39 is fastened. The upper needle cylinder 40 is fastened to a gear 41 which is fastened to a running ring 42 rotatably mounted in a bed-plate 43. The running ring 38 is 55 rotatably mounted in the bed-plate 44 and said bed-plates are suitably mounted upon the frame of the machine, all in a manner well known to those skilled in this art.

A rotary motion is imparted to the upper 60 needle cylinder 40 as well as to the lower needle cylinder 39, by a gear which meshes into the gear 41, said gear being fastened to the upright shaft 35, but not shown in the drawings.

65 A hand wheel 45 is fastened to the main

shaft 30 whereby a rotary motion may be imparted to said shaft, when desired, by hand. Said shaft is rotated by power by means of a belt 46 which engages a clutch pulley 47 having clutch arms 48 pivotally mounted thereon and engaging another member 49 of said clutch, which member is slidably mounted upon the shaft 30 and is splined thereto. The member 49 is provided with an annular groove 50 in its periphery 75 into which project pins 51 which are fastened to an arm 52 which, in its turn, is fastened to a rock-shaft 53 mounted to rock in bearings 54 which project from the side frame 26.

The rock-shaft 53 has two arms 55 and 56 fast thereto by means of which it may be operated by hand. It also has an arm 57 fast thereto which is connected by a link 58 to a screw 59 fast to the rotary member 21 and, therefore, when said rotary member is released, as hereinbefore described, the link 58 will rock the arm 57 and the rock-shaft 53, whereby the arm 52 will be rocked to move the slidable member 49 of the clutch 80 away from the clutch pulley 47, thus releasing the clutch arms 48 and allowing the clutch pulley 47 to rotate freely upon the shaft 30.

The rock-shaft 53 is provided with still 95 another arm 60 having a stop-screw 60' in screw-threaded engagement therewith and adapted to bear against the side frame 26 when the clutch member 49 is moved to disengage the clutch from the main driving 100 shaft.

When the electric circuit is broken, as hereinbefore described, it is desirable that the rotation of the main shaft 30 and, therefore, the movement of the parts driven thereby, should be stopped as soon as possible in order that the yarn may not run off the needles, with the resultant inconvenience, loss of time and waste of material. To this end a friction brake 61 is provided which 110 consists of a collar 62 fastened by a set-screw 63 to the shaft 30. Upon this collar is rotatably mounted a ratchet 64 which is held in frictional engagement with the collar 62 by annular washers 65 of a suitable material 115 to resist wear, said annular washers being held against one face of the ratchet 64 by an annular plate 66 and screws 67 which have screw-threaded engagement with the collar 62 and extend through the washers 65 and plate 66, said screws being encircled by springs 68 which bear against the plate 66 and are forced thereagainst by screwing the screws 67 into the collar 62, thus forcing the washers 65 toward and against the ratchet 120 64 with a yielding pressure.

A pawl 69 is pivoted at 70 to an ear 71 on the cross-head 24 and has a pin 72 projecting from its upper end through a slot 73 in an arm 74 which is pivotally connected 125

at 75 to the spring driven member 21. A lug 76 is fastened to the spring driven member 21 and is adapted, when said spring driven member rotates, to engage the arm 5 74 and throw the pawl 69 into engagement with the ratchet 64, thus stopping the rotation of the ratchet 64 and, through the friction washers 65 and collar 62, causing the shaft 30 to be stopped quickly, although

10 not instantaneously, there being a possibility for the shaft to continue its rotation for a slight distance, after the pawl 69 engages the ratchet 64, between the washers 65 and the collar 62.

15 It is desirable, as hereinbefore set forth, that the circuit should be broken after the clutch mechanism is thrown out, in order that the batteries may not be weakened or run down and for this purpose a circuit 20 making and breaking device 77 is provided consisting of a casing 78 (Fig. 7) fastened to the cross head 24 and having terminals 79 and 80 adapted to be engaged by a contact plate 81 having a stem 82 slidable in 25 the casing 78 and provided with a head 83. A spring 84 holds the contact plate 81 normally out of contact with the terminals 79 and 80. Said plate 81 is brought into contact with said terminals by a cam-shaped

30 projection 85 which projects from the rear face of an arm 86 pivoted at 87 (Fig. 3) to the cross head 24. This arm is connected by a link 88 to the arm 55 by a stud 89 which projects through a slot 90 in said link 88. 35 A spring 91 is connected to the link 88 at one end and to the stud 89 at the other.

The vertical shaft 18 is rotatably mounted upon the bed-plate 44, as seen in Fig. 8, and is rotated by a spring 92 in a direction 40 to bring a pin 93 fast to said shaft against a bracket 94 in the lower end of which the shaft 18 is rotatably mounted. The shaft 18 is rotated in an opposite direction to that in which it is rotated by the spring 92, or 45 toward the right (Fig. 1), to disengage the tripper arm 19 from the arm 20 by the armature lever 17, the armature lever being actuated by the electromagnet 16, as hereinbefore set forth, said electromagnet forming 50 a part of the electric circuit 95.

The electromagnet 16 is fastened to the cross head 24 and is connected by an electric wire 96 (see Fig. 1) to the battery 97 and by a wire 98 to one of the terminals 99 which 55 connects with one of the mercury contacts 13. The other terminal 100 is connected by a wire 101 to the terminal 79 of the circuit making and breaking device 77. The other terminal 80 of said make and break device 60 is connected by a wire 102 to the electromagnet 16, thus completing the circuit.

Referring, now, to the circuit closing device illustrated in Figs. 9, 10 and 11, the drop wire 9 is held out of contact with the 65 contacts 13 by the strand of yarn 12 which

passes from a yarn mass 104 through a guide eye 105 provided in the auxiliary frame 106 through a yarn scraper 107 to the guide eye or bend 11 formed in the drop wire 9, thence upwardly through a stationary guide-eye 76 109, through a movable guide-eye 110 and through stationary guide-eyes 111, 112, 113, and 114 to the primary needles 115 of the knitting machine.

The movable guide-eye 110 is fastened to 75 a U-shaped lever 116 pivoted at 117 to the block 8. A pin 118, constituting an arm, extends from the lever 116 over the closed end of the U-shaped drop wire 9 and forms a stop therefor to prevent said eye 110 from being moved away from the contacts 13 more than a certain distance. It will be understood that as the lever 116 is rocked upon its pivot, the pin 118 will contact with the drop wire 9 and force the same downwardly until the contact points of said wire engage the contacts 13 and complete the circuit.

It will also be understood that one of the circuit closing devices 5 will be supplied for 90 each feed of yarn in a knitting machine.

In some cases the clutch pulley is located on the opposite side of the machine from that in which it is shown in the drawings in this case, but it will be seen that the 95 mechanism is clearly applicable to such an arrangement of parts, as the rocker-shaft 53 with its connected parts can be located as well at one side of the machine as the other, and the rocker arm 86 can be operated 100 to open and close the circuit by means of the electric switch 77 as well in one case as the other, the cam-shaped projection 85 being equally operative whether the arm 86 which carries it is moved toward the right 105 or left relatively to the switch 77.

The general operation of the mechanism hereinbefore specifically described is as follows: Assuming the parts to be in the position illustrated in Figs. 1, 2 and 3 of the 110 drawings, and that the normal feeding of the yarn 12 is interfered with, either by the breaking of the same or by abnormal tension thereon, the drop wire 9 will, in the case of the breaking of the yarn or the running out 115 of the supply thereof, drop by its own weight until the legs 10 engage the contacts 13, thus closing the electric circuit 95. As soon as said electric circuit is closed the armature lever 17 will be drawn toward the 120 electromagnet 16 thus releasing the arm 20 and allowing the spring actuated member 21 to be rotated. As it is rotated the link 58 will move the arm 57 toward the left (Fig. 2) rocking the shaft 53 and the arm 52 fast 125 thereto in the proper direction to slide the clutch member 49 out of engagement with the clutch arms 48 and thus releasing the clutch pulley 47 from engagement with the shaft 30. The driving shaft being released 130

from the clutch it is free to be stopped by the friction brake 61 which is thrown into operative engagement by the arm 74 which rocks the pawl 69 into engagement with the 5 ratchet 64 and thus causes the shaft 30 to be brought to a stop, as hereinbefore described.

When the rocker shaft 53 is rocked, as hereinbefore set forth, the stud 89 will engage the right hand end of the slot 90 (Fig. 10 3) and move the link 88 toward the right, thus rocking the arm 86 and moving the cam-shaped projection 85 thereon out of engagement with the head 83 and allowing the plate 81 to be thrown out of contact with 15 the terminals 79 and 80, thus breaking the electric circuit.

By means of the levers 55 and 56 it will be understood that the electric circuit may at any time be broken and the clutch thrown 20 out of engagement with the shaft 30 from either the front or rear of the machine and also, if desired, the electric circuit may be broken by the operator pushing the link 88 toward the right (Fig. 3) without disengaging 25 said clutch from the shaft. In the latter case when the link 88 is released by the operator the spring 91 will move the rocker-arm 86 back to the position in which it is shown in Fig. 2. This is a very convenient construction 30 in cases where the operator wishes to break the electric circuit without stopping the machine.

When the yarn 12 is prevented from feeding freely and abnormal tension is brought 35 to bear thereon, the lever 116 will be tipped upon its pivot 117 by the yarn by means of the guide-eye 110, and when this happens the pin 118 will engage the drop wire 9 and push the same downwardly until the legs 10 40 contact with the mercury contacts 13, thus completing the circuit and operating the stop mechanism, as hereinbefore described, to stop the machine.

Having thus described my invention, what 45 I claim and desire by Letters Patent to secure is:

1. A knitting machine having, in combination, a driving shaft, mechanism embodying a clutch constructed and arranged to rotate 50 said shaft, an electric circuit including two devices for opening and closing said circuit, one of said devices constructed and arranged to engage a strand of yarn and adapted to be operated when the normal feeding of said 55 yarn is interrupted to close said circuit, a brake constructed and arranged to stop the rotation of said shaft, a rotary member and connections therewith constructed and arranged upon the closing of said circuit to

first disengage said clutch from said shaft, 60 second, throw said brake into operative engagement with said shaft to stop its rotation, and third, operate the other of said devices to open said circuit.

2. A knitting machine having, in combination, a driving shaft, mechanism embodying a clutch constructed and arranged to rotate said shaft, an electric circuit including two devices for opening and closing said circuit, one of said devices constructed and arranged to engage a strand of yarn and adapted to be operated when the normal feeding of said 65 yarn is interrupted to close said circuit, a brake constructed and arranged to stop the rotation of said shaft, a spring-actuated 70 rotary member and connections therewith, a tripper arranged to lock said rotary member against rotation, said tripper constructed and arranged upon the closing of said circuit to release said rotary member and said 75 connections, whereupon said rotary member and said connections will first disengage said clutch from said shaft, second throw said brake into operative engagement with said shaft to stop its rotation, and third operate the other of said devices to open said circuit.

3. A knitting machine having, in combination, a driving shaft, mechanism embodying a clutch constructed and arranged to rotate said shaft, an electric circuit including two devices for opening and closing said circuit, one of said devices constructed and arranged to engage a strand of yarn and adapted to be operated when the normal feeding of said 90 yarn is interrupted to close said circuit, a brake constructed and arranged to stop the rotation of said shaft, a rotary member and connections therewith constructed and arranged upon the closing of said circuit to first disengage said clutch from said shaft, second, throw said brake into operative engagement with said shaft to stop its rotation, and third, operate the other of said devices to open said circuit, the connections from said rotary member to said last-named device being constructed and arranged to allow said device to be manually operated independent of said clutch and brake.

In testimony whereof I have hereunto set my hand in presence of two subscribing witnesses.

WILLIAM W. BURKE.
